METHOD OF CLOSING CONTAINERS

Herbert H. Leonard, East Aurora, and Royal T. Moore, Buffalo, N. Y., assignors to Consolidated Packaging Machinery Corporation, a corporation of New York

Application January 18, 1938, Serial No. 185,502

14 Claims. (Cl. 93—6)

The present invention relates to the formation of a closure for flexible containers and, more particularly, to the formation of a closure upon the open end of filled paper bags.

5 In the packaging of finely divided and pulv-
erulent materials it is desirable to form a clo-
sure which will effectively prevent the escape of
such materials.

Certain materials are subject to deterioration
10 or loss of desirable characteristics upon exposure
to air or to moisture or to contaminating sub-
stances with which air may be laden. In the
packaging of such materials, it is desirable to
form a closure which will effectively prevent the
15 ingress of air to the contents.

It is an object of the present invention to pro-
vide a closure having the desirable characteris-
tics above set forth.

It is a further object of this invention to form
20 a closure having the desirable characteristics
above set forth which may be readily formed by
manual manipulation or by the operation of suit-
able automatic machinery.

Other and further objects of the present in-
25 vention will become more apparent from a con-
sideration of the following description taken in
connection with the drawings accompanying and
forming a part of this specification.

In the drawings,

30 Fig. 1 illustrates an open ended filled container
of the type which may be closed according to
our invention;

Figs. 2, 3, 4 and 5 illustrate successive steps in
35 the formation of a closure according to our in-
vention;

Fig. 6 is a perspective view of a container hav-
ing a completed closure formed thereon in ac-
cordance with our invention;

Fig. 7 illustrates a step in the formation of a
40 modified form of closure according to our in-
vention;

Fig. 8 is a perspective view of a container upon
which a completed closure of the form illustrated
in Fig. 7 has been formed; and

45 Fig. 9 is a broken perspective view of a con-
tainer upon which a completed closure of further
modified form has been formed.

Similar characters of reference indicate simi-
50 lar parts throughout the several views.

Referring now to Fig. 1 of the drawings, 10 in-
dicates the upper portion of a flexible walled con-
tainer such as a paper bag. The bag is filled
to a point adjacent its mouth with material 11.
55 The portion of the bag 10 extending above the

line of contents 11 comprises oppositely disposed
wall portions 12, 13 and 14, 15, respectively.

In the formation of a closure upon the bag
illustrated in Fig. 1, the wall 12 is folded in-
wardly and down upon the upper surface of the 5
contents 11. The folding of the wall 12 will
cause portions of the walls 14 and 15 to fold in-
wardly and upon themselves along angularly dis-
posed lines 16 and 17, as seen in Fig. 2.

The wall 13 may now be folded inwardly and 10
down upon the contents 11 and upon the upper
surface of the folded wall 12. As seen in Fig.
3, the folding of the wall 13 will cause portions
of the walls 14 and 15 to be folded inwardly upon
themselves along the lines 18 and 19. It will 15
also be seen in Fig. 3 that the wall 13 overlaps
a substantial portion of the wall 12 and to this
end it is of course necessary that the level of
contents 11 shall be sufficiently below the mouth
of the bag to leave ample material for over- 20
lapping. It will also be seen that the portions
of walls 14 and 15, which are folded with the
wall 13, will overlap those portions of the walls
14 and 15 which have been folded with the wall 12.

In order to secure the walls 12 and 13 in their
overlapped relationship upon the top of contents
11, a suitable adhesive 20 may be applied to the
upper surface of wall 12, as shown in Fig. 2.
The overlapping portions of the walls 14 and 25
15 may be secured by adhesive 21 applied to a
suitable area of the portions of the walls 14 and
15 which are folded with the wall 12.

When the walls have been folded and secured
in the positions shown in Fig. 3, it will be seen
that the walls 14 and 15 have been formed into 30
flaps 22 and 23 having bodies of generally tri-
angular configuration defined by the lines 16, 18
and 17, 19, respectively. At the upper tip or ex-
tremity of each of the flaps 22 and 23 there will
be an opening 24 which communicates directly 35
with the contents of the bag. If the flaps 22 and
23 are simply folded down upon the upper sur-
face of the bag, these openings will form passage-
ways through which the contents of the bag may
escape or through which air may have access 40
to the contents.

According to our invention, the passageways
extending from the openings 24 to the contents
are effectively closed. In the form of closure
illustrated in Figs. 4, 5 and 6, the flaps 22 and 23 45
50 are folded inwardly upon themselves along lines
25 and 26. The fold lines 25 and 26 are located
above the level of the contents a distance some-
what less than one-half of the total height of
the flaps 22 and 23. The folded portions of the 55

flaps 22 and 23 are brought into contact with the base portions thereof and the tips of the flaps are allowed to contact the upper surface of the bag and, accordingly, to fold reentrantly upon themselves along the lines 27 and 28, as seen in Fig. 5.

The reentrantly folded flaps 22 and 23 may now be folded inwardly and down upon the upper surface of the bag into the position shown in Fig. 6. A suitable adhesive 29 may be applied to the inner surfaces of the flaps, as seen in Fig. 5, in order to secure the flaps in the final position illustrated in Fig. 6.

From a consideration of Figs. 4, 5 and 6 it will be seen that the passageway extending from the openings 24 to the contents 11 has been folded upon itself in reversely disposed directions and that such folds are adhesively secured in flattened condition. This folding of the passageway will form an effective barrier to the escape of material and to the access of air to the material.

From an inspection of Fig. 6 it will be apparent that the openings 24 in the tips of the flaps 22 and 23 are confined between the flap bodies and the body of the bag and are completely surrounded by adhesively secured surfaces which form an effective barrier to the escape of material from the openings as well as the access of air to the openings.

The closure above described may be manually formed or may be formed upon suitable automatic machinery. In either event the filled bag may be supported in any convenient manner. If so desired, the supporting means may be designed to square or otherwise shape the walls of the bag body in a predetermined manner.

In Figs. 7 and 8 we have illustrated a modified form of closure having the desirable features set forth as objects of our invention. In this form of our invention the flaps 22 and 23 are formed as shown in Figs. 1, 2 and 3. The extreme portions of the flaps 22 and 23 are folded or doubled inwardly upon the bodies of the flaps along lines 30 and 31 located adjacent the tips of the flaps. The folded flap tips may be creased along the lines 30 and 31 in order to form a barrier in the passageway extending between the openings 24 and the contents 11. Flaps 22 and 23, folded as shown in Fig. 7, may then be folded inwardly and down upon the top of the bag into the position illustrated in Fig. 8. A suitable adhesive 32 may be applied to the inner surfaces of the folded flaps while in the position illustrated in Fig. 7 in order to secure the same in the final position illustrated in Fig. 8.

From a consideration of Fig. 8, it will be apparent that the openings 24 in the extremities of the flaps are confined between the bodies of the flaps and the body of the bag and are surrounded by adhesively secured surfaces which form an effective barrier to the egress of material therefrom and to the ingress of air therethrough.

In Fig. 9 we have illustrated a further modified form of closure having the desirable features set forth as objects of our invention. In this form the flap 23 has been folded outwardly upon itself adjacent the tip. The flap 23 is then folded outwardly along its base and into contact with the body of the bag. The folded tip 33 thus becomes confined between the body of flap 23 and the substantially vertical side wall portions of the bag body. The folded flap 23 may be adhesively secured in the position shown

in Fig. 9. While in Fig. 9 we have shown only the flap 23, it is obvious that the opposite flap such as shown at 22 in Fig. 3 may be similarly folded and secured.

From a consideration of the above description of preferred forms of our invention, it will be apparent that we have provided a closure having the characteristics above set forth as desirable and which achieves the objects of our invention. While the above detailed description has been made in order to comply with the statutes, it is obvious that modifications and variations in form and detail may be resorted to by those skilled in the art. The above detailed description is therefore to be taken in an illustrative rather than in a limiting sense and it is our intention that the scope of our invention shall be limited only by the appended claims.

We claim:

1. The method of closing a filled bag having walled portions defining an open mouth comprising, folding opposite wall portions of the bag into overlapping relation into the plane of the top of the contents of the bag in such manner as to form opposed flaps extending outside the area of the contents, folding each of said flaps upon itself, and folding said folded flaps upon the overlapped wall portions in the plane of the top of the contents.

2. The method of closing a filled bag having wall portions defining an open mouth comprising, folding opposite wall portions of the bag into overlapping relation against the contents of the bag in such manner as to form opposed flaps extending outside the area of the contents, folding each of said flaps upon itself, and folding said folded flaps against the filled portion of the bag.

3. The method of closing a filled bag having wall portions defining an open mouth comprising, folding opposite wall portions of the bag into overlapping relation against the contents of the bag in such manner as to form opposed flaps having bodies extending outside the area of the contents, folding the extremities of said flaps upon the bodies thereof, and folding said folded flaps against the filled portion of the bag in such manner as to confine said flap extremities between the bag and the bodies of the flaps.

4. The method of closing a filled bag having wall portions defining an open mouth comprising, folding opposite wall portions of the bag into overlapping relation against the contents of the bag in such manner as to form opposed flaps extending outside the area of the contents, folding each of said flaps twice upon itself, and folding said folded flaps against the filled portion of the bag.

5. The method of closing a filled bag having wall portions defining an open mouth comprising, folding opposite wall portions of the bag into overlapping relation into the plane of the top of the contents of the bag in such manner as to form opposed flaps extending outside the area of the contents, folding each of said flaps twice upon itself, and folding said folded flaps upon the overlapped wall portions in the plane of the top of the contents.

6. The method of closing a filled bag having wall portions defining an open mouth comprising, folding opposite wall portions of the bag into overlapping relation into the plane of the top of the contents of the bag in such manner as to form opposed flaps having bodies extending outside the area of the contents, forming reentrant

5 folds in the extremities of said flaps, and folding said folded flaps upon the overlapped wall portions of the bag in such manner as to confine said flap extremities between said overlapped wall portions and the bodies of said flaps.

7. The method of closing a filled bag having wall portions defining an open mouth comprising, folding opposite wall portions of the bag into overlapping relation into the plane of the top 10 of the contents of the bag in such manner as to form opposed flaps extending outside the area of the contents, folding said flaps along lines generally parallel to the plane of the contents and spaced therefrom at such a distance as to bring 15 the extreme portions of said flaps into the plane of the top of the contents, and folding the remainder of said flaps upon said extreme portions and said overlapped portions into the plane of the top of the contents.

20 8. The method of closing a filled bag having wall portions defining an open mouth comprising, folding opposite wall portions of the bag into overlapping relation into the plane of the top of the contents of the bag in such manner as to 25 form opposed flaps extending outside the area of the contents, adhesively securing said opposite wall portions in overlapping relation, folding each of said flaps upon itself, folding said folded flaps upon the overlapped wall portions in the plane of 30 the top of the contents, and adhesively securing said flaps to said overlapped wall portions.

9. The method of closing a filled bag having wall portions defining an open mouth comprising, folding opposite wall portions of the bag into 35 overlapping relation into the plane of the top of the contents of the bag in such manner as to form opposed flaps extending outside the area of the contents, adhesively securing said opposite wall portions in overlapping relation, folding each 40 of said flaps upon itself, folding said folded flaps upon the overlapped wall portions in the plane of the top of the contents, and adhesively securing said flaps to said overlapped wall portions.

10. The method of closing a filled bag having 45 wall portions defining an open mouth comprising, folding opposite wall portions of the bag into overlapping relation against the contents of the bag in such manner as to form opposed flaps having bodies extending outside the area of the contents, adhesively securing said opposite wall 50 portions in overlapping relation, folding the extremities of said flaps upon the bodies thereof, folding said folded flaps upon the body of the bag in such manner as to confine said flap extremities between the body of the bag and the 55 bodies of the flaps respectively, and adhesively securing said flaps against the filled portion of the bag.

11. The method of closing a filled bag having wall portions defining an open mouth comprising, folding opposite wall portions of the bag into overlapping relation against the contents of the bag in such manner as to confine said flap extending outside the area of the contents, adhesively securing said wall portions in overlapping relation, folding each of said flaps twice upon itself, folding said folded flaps against the filled portion of the bag, and adhesively securing 10 said flaps to said portion.

12. The method of closing a filled bag having wall portions defining an open mouth comprising, folding opposite wall portions of the bag into overlapping relation into the plane of the top of the contents of the bag in such manner as to form opposed flaps extending outside the area of the contents, adhesively securing said opposite wall portions in overlapping relation, folding each 15 of said flaps twice upon itself, folding said folded flaps upon the overlapped wall portions into the plane of the top of the contents of the bag, and adhesively securing said flaps to said overlapped wall portions.

13. The method of closing a filled bag having wall portions defining an open mouth comprising, folding opposite wall portions of the bag into overlapping relation against the contents of the bag in such manner as to form opposed flaps having bodies extending outside the area of the contents, adhesively securing said opposite wall portions in overlapping relation, forming reentrant folds in the extremities of said flaps, folding said folded flaps against the filled portion of the bag in such manner as to confine said flap extremities between the bag and the bodies of said flaps, and adhesively securing said flaps to the bag.

14. The method of closing a filled bag having wall portions defining an open mouth comprising, folding opposite wall portions of the bag into overlapping relation into the plane of the top of the contents of the bag in such manner as to form opposed flaps extending outside the area of the contents, adhesively securing said wall portions in overlapping relation, folding said flaps along lines generally parallel to the plane of the contents and spaced therefrom at such a distance as to bring the extreme portions of said flaps into the plane of the top of the contents, folding the remainder of said flaps upon said extreme portions and said overlapped portions into the plane of the top of the contents, and adhesively securing said flaps to said overlapped wall portions.

55 HERBERT H. LEONARD.
ROYAL T. MOORE.
